STITCH REMOVER

Arvi Alto, Wareham, Mass.

Application November 23, 1934, Serial No. 754,529

2 Claims. (Cl. 12—17)

This invention relates to shoe repairing machines and more particularly to the production of a simple and efficient stitch remover especially adapted for removing stitches from shoes which are to be repaired or resoled.

A further object of this invention is the production of a simple and efficient means for removing stitches from the sole of a shoe consisting of a plurality of picker elements, one arranged behind the other to facilitate the picking or lifting of the old stitches from the sole of the shoe so as to completely remove the stitches to permit of the resoling of a shoe without the former stitches showing around the edge of the sole.

A still further object of this invention is the production of a simple and efficient stitch remover, one element of which is a spring supporting table used in conjunction with the picker elements to yieldably support the sole of the shoe so as to firmly hold the sole in position for engagement with the picker elements and also to allow the sole to be pushed downwardly away from the picker elements to facilitate the withdrawing of the stitches from the sole.

Other objects and advantages will be apparent throughout the following specification and claims.

In the drawing:—

Figure 1 is a side elevation of the improved stitch remover;

Figure 2 is an end elevation of the improved device, the supporting bench being shown in section;

Figure 3 is a top plan view of the improved device;

Figure 4 is an end elevation of the stitch remover looking in the direction of the picker elements and showing the device at its opposite end with respect to Figure 2;

Figure 5 is an enlarged sectional view through the operating shaft and illustrating the action of the picker hooks or elements;

Figure 6 is a vertical sectional view through the spring pressed supporting table;

Figure 7 is a horizontal section taken on line 7—7 of Figure 6.

By referring to the drawing, it will be seen that 10 designates the work bench which carries a platform 11 preferably of metal having upwardly extending braces 12 secured thereto, the platform 11 preferably fitting over the edge of the bench and having a skirt portion 13 overhanging the edge of the bench 10, as shown. The braces 12 are in the nature of uprights or standards which have forwardly extending overhanging end portions 14, and these end portions 14 carry the

suspending journals 15 in which journals 15 is mounted the driving shaft 16, the same being journaled in any suitable or desired manner common to the trade. A driving pulley 17 is carried by the shaft 16 over which is trained a driving belt 18 for the purpose of supplying power to the shaft. The overhanging end portions 14 are connected by a connecting brace 19 and one of the overhanging end portions 14 is provided with a laterally extending web 20, which web is provided on its front edge with an upwardly bent shield 21 adapted to rest against the upper of the shoe S, as shown in Figure 4. The shaft 16 carries at its outer end a pair of spaced picker elements 22, each picker element being preferably provided with two picker hooks 23, the ends of which are pointed and wedge-shaped, as shown in detail in Figure 5, and are curved forwardly in the direction of travel or rotation of the picker hooks 23 to provide beak-like points 24. These beak-like points 24 will permit the points to dig under the stitches of the shoe and because of the wedge-like shape of the beak-like points and the direction of travel, a pulling action will be provided to lift the stitches and pull the stitches out of engagement with the sole. Two of these picker elements 22 are preferably provided, one directly behind the other to provide a following-up action and insure of the removal of all of the stitches. Should it be necessary the forward picker element 22 would break the thread and the following picker element 22 arranged in spaced relation thereto, as shown in Figure 1, would provide the follow-up action to grip the stitches and pull the same out of engagement with the sole.

To facilitate the operation of the pulling action, there is provided a spring pressed sole supporting table 25, illustrated in detail in Figure 6, which spring pressed table 25 is provided with a stop ledge 26 against which the shoe sole A of the shoe S may abut. This spring pressed table 25 is provided with a depending guide leg 27 having a dove-tail tongue 28 upon one side thereof, which dove-tail tongue 28 travels within the dove-tail socket or groove 29 formed in the adjoining face of the guide support 30. This guide support 30 comprises a vertically extending leg 31 and a horizontally extending leg 32, the horizontally extending leg 32 being provided with an elongated slot 33 through which an anchoring bolt 34 extends. A thumb nut 35 is carried by the bolt 34 for the purpose of securing the guide support 30 in an adjusted position upon the platform 11. This guide support 30 may be adjusted

to or from the edge of the platform 11 by sliding the slot portion 33 over the bolt 34 and then tightening the nut 35 to the adjusted position. The guide support 39 carries an upstanding pin

- 5 36 upon which is mounted a coil spring 37 and the pin 36 is seated within a socket cup 38 carried by the under face of the table 25, the spring 37 engaging the lower edge of the cup 38 and normally urging the table 25 upwardly. Due to 10 this structure, a resilient support will be provided for the sole of the shoe and the operator may assist in providing the pulling action for the picker elements 22 by pushing downwardly upon the sole of the shoe which rests upon the spring 15 pressed table 25, the spring 37 normally returning the table 25 to its extended position.

From the foregoing description it will be seen that a very simple and efficient stitch remover has been provided in the nature of the picker 20 elements 22 and also in conjunction with the spring pressed table which supports the shoe yieldably against the action of the picker elements. Furthermore, it should be understood that a very durable and sturdy spring pressed 25 supporting element has been provided upon which the sole of the shoe may rest, this support being also adjusted to the various widths of soles to facilitate the gripping of the stitches by the 30 beak-like ends of the picker hooks 23.

In carrying out this invention, the sole is first cut from the welt, and the device above described may then be used for pulling or removing the 35 stitches from the welt.

It should be understood that certain detail changes in the mechanical construction, combination and arrangement of parts may be employed without departing from the spirit of the

invention, so long as such changes fall within the scope of the appended claims.

Having described the invention, what I claim as new is:—

1. A device of the class described comprising an angle guide support having a vertically extending member and a horizontally extending member, the horizontally extending member being longitudinally slotted, an anchoring bolt passing through the slot portion of the horizontally extending portion, means engaging the bolt for locking the guide support in an adjusted position, a table member having a depending leg slidably engaging the vertically extending portion of the 10 guide support, a guiding pin carried by the guide support and engaging the table member, and spring means interposed between the table member and the guide support for yieldably supporting the table member.

2. A device of the class described comprising an angle guide support having a vertically extending member and a horizontally extending member, the horizontally extending member being longitudinally slotted, an anchoring bolt passing through the slot portion of the horizontally extending portion, means engaging the bolt for locking the guide support in an adjusted position, a table member having a depending leg slidably engaging the vertically extending portion of the 15 guide support, a guiding pin carried by the guide support and engaging the table member, and spring means interposed between the table member and the guide support for yieldably supporting the table member.

3. A device of the class described comprising an angle guide support having a vertically extending member and a horizontally extending member, the horizontally extending member being longitudinally slotted, an anchoring bolt passing

20 through the slot portion of the horizontally extending portion, means engaging the bolt for locking the guide support in an adjusted position, a table member having a depending leg slidably

25 engaging the vertically extending portion of the guide support, a guiding pin carried by the guide support and engaging the table member, and spring means interposed between the table member and the guide support for yieldably supporting the table member.

4. A device of the class described comprising an angle guide support having a vertically extending member and a horizontally extending member, the horizontally extending member being longitudinally slotted, an anchoring bolt passing

30 through the slot portion of the horizontally extending portion, means engaging the bolt for locking the guide support in an adjusted position, a table member having a depending leg slidably

35 engaging the vertically extending portion of the guide support, a guiding pin carried by the guide support and engaging the table member, and spring means interposed between the table member and the guide support for yieldably supporting the table member, and the depending leg of the table member and the vertically extending portion of the guide support being interfitted with a dovetail slidable connection.

ARVI ALTO.
